UNITED STATES PATENT OFFICE.

HERMAN B. FRIEDMAN, OF NEW YORK, N. Y.

INTERCONNECTED STEAM-BOILER AND WATER-HEATER.

1,106,087.

Specification of Letters Patent.

Patented Aug. 4, 1914.

Application filed October 22, 1913. Serial No. 796,635.

To all whom it may concern:

Be it known that I, HERMAN B. FRIEDMAN, a citizen of the United States, and resident of the city of New York, in the county of New York and State of New York, have invented certain new and useful Improvements in Interconnected Steam-Boilers and Water-Heaters, of which the following is a specification.

The present invention relates to an interconnected steam boiler and water heater, specially adapted for use in tenement houses and apartment houses where a hot water supply is continuously needed for bathing, washing and other purposes, and steam for heating.

One of the objects of the present invention is to combine a water heater and a steam boiler in such a manner that the products of combustion from the fire-box of one of the same can be led, at will, into that of the other one, the two elements being, however, connected in such a manner that when the communication between the two fire-boxes thereof is closed, no heat will be transmitted from the water heater to the steam boiler, and vice versa.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:—

Figure 1 is a central longitudinal section taken through a steam boiler and a water heater interconnected in accordance with the present invention; Fig. 2 is a front elevation of the same; and Fig. 3 is a section taken on line 3—3 of Fig. 2.

In the drawings, the numerals 10 and 11 indicate two independent cylindrical boiler shells, having heads 12 and 13, respectively. Each structure rests on legs 14. The shells and heads are provided with heat insulating coverings 15 and 16, respectively, for a well

known purpose. In the shell 10 is disposed a fire-box 17 and in the shell 11 a fire-box 18, both boxes being, preferably, cylindrical and having arranged near their bottoms grates 19 and 20, respectively, on which fires may be built. Below the grates are located ash-pits 21 and 22, respectively, to which access may be had through collars 23, which extend beyond their respective boiler shells and are provided with dampers 24 and 25, respectively, which are hinged to the said collars. For the admission of fuel, doors 26 and 27 are provided, such doors being hinged to collars 27', which extend from the shells to the respective fire-boxes. The two fire-boxes communicate with each other through a tubular member 28, in which is disposed a disk shutter 29, which is adapted to be actuated by means of a handle 30, that is attached to the spindle 31 of the shutter. By means of this shutter, the communication between the two fire-boxes may be controlled for a purpose hereinafter to be described.

From the top of each fire-box leads a flue 32, extending up toward and through the heads 12 and 13, respectively, to be connected with the chimney. The flues, which serve to conduct the products of combustion toward the chimney, are bent in the form of coils, as clearly shown in Figs. 1 and 3 of the drawings. By forming these flues in the manner described, obviously the flow of the products of combustion will be retarded and their heat effectively given up to the water that surrounds the said flues and the fire-boxes in the two boilers. In each flue is arranged a damper 33 of the well known construction, which is adapted to be operated manually to control the draft in the flue. The flues may be made, preferably, detachable, to permit them to be removed from the shells for cleaning purposes, etc.

The shell 11 and the elements located therein form a water heater, the water entering the same through a supply pipe 34. A pipe 35 is tapped into the head 13 of the heater for the purpose of conducting the hot water to the place at which it is to be used. The shell 10 with the elements therein forms a steam boiler, and is provided with a water supply pipe 36 near its bottom and with a steam pipe 37 in the head 12 of the same. The normal water level in the boiler is indicated by a line denoted by the numeral 38, the height of the water within the

said boiler being shown by a water gage 39 of any suitable construction. To indicate the pressure of the steam in the boiler, a steam gage 40 is provided, a safety valve 41 being made use of for preventing the pressure of the steam exceeding a certain predetermined point. The damper 24 of the boiler may be set by hand, or it may be actuated automatically by steam pressure by a mechanism 42, which is connected by the intermediary of a plurality of levers 43 and a rod 44 with the said damper. The particular construction of the mechanism 42 need not be described as the same does not form an essential part of the invention.

The operation of this system is as follows: In cold weather, when both hot water and steam are needed, fire is placed into both fire-boxes. The shutter 29 is set to its open position to establish a communication between the two fire-boxes so as to equalize the temperature in the boiler and heater. Water, admitted into the heater, rises therein up to its top. In the steam boiler the level of the water is maintained at the height above mentioned. The water in the heater surrounds entirely the fire-box and the coiled flue, and will thus be quickly and economically heated, to be conducted through the pipe 35 to the place or places at which it is to be used. In the steam boiler the water is converted into steam and conducted through the pipe 37 to radiators or other places. The damper 24 of the steam boiler is closed by the steam pressure as the same exceeds the normal, and is opened automatically to an extent proportionate to the decrease of pressure in said boiler. If mainly steam is needed, the fire-box in the steam boiler is fired only, the

shutter 29 being left open so that the products of combustion will escape through both flues, generating thereby steam and heating the water in the heater. If only hot water is needed, the shutter 29 is closed and fire is placed only in the fire-box 18 within the heater. Obviously, if steam only is to be generated, the shutter 29 is set to its closing position and only the fire-box 17 in the steam boiler fired. It is to be observed that when the shutter 29 in the tubular member is set to its closing position, no heat will be transmitted from the boiler to the heater and vice versa, or in other words when the boiler only is fired, the entire products of combustion serve to generate steam, the water in the heater being maintained at its initial temperature, and in a similar manner if the heater is fired only, the temperature of the water in the boiler will not be affected.

What I claim is:—

The combination with two independent shells that are spaced apart and form a steam boiler and a water heater, respectively, of a fire-box arranged within each shell, a water-supply pipe leading to each shell, an outlet pipe connected to each shell, a flue in the form of a coil extending through each shell and connected to each respective fire-box, and a valve controlled connection between said fire-boxes.

Signed at New York, in the county of New York, and State of New York, this 10th day of October, A. D. 1913.

HERMAN B. FRIEDMAN.
